[57] CLAIM

The ornamental design for a marker, as shown and described.

DESCRIPTION

FIG. 1 is a top front perspective view of a marker, showing my new design;

FIG. 2 is a bottom front perspective view thereof;

FIG. 3 is a top front perspective view of the marker as it appears when folded;

FIG. 4 is a bottom front perspective view of the marker as it appears when folded.

The rear of the marker is substantially planar.

FIG. 1

FIG. 2

FIG. 3

FIG. 4
